(57) CLAIM

I claim the ornamental design for a water craft, as shown and described.

DESCRIPTION

FIG. 1 is a top plan view of a water craft showing my new design.

FIG. 2 is a bottom plan view thereof.

FIG. 3 is a left side elevational view thereof, the right side elevational view being a mirror image thereof.

FIG. 4 is a front elevational view thereof; and,

FIG. 5 is a rear elevational view thereof.

The broken or dashed lines shown in the drawings are for illustrative purposes only and form no part of the claimed design.

The shading lines shown in the drawings represent the three-dimensional contour of the design, and are not intended to indicate surface decoration.
